OTHER PUBLICATIONS

Firekim (on-line), no date available. Retrieved from Internet Nov. 3, 2022, URL: <http://www.firekim.co.kr/en/brand/sensor.php> (2 pages).*Primary Examiner — Kimberly Barnes(74) *Attorney, Agent, or Firm* — Dorsey & Whitney LLP(57) **CLAIM**

I claim the ornamental design for a fire extinguisher, substantially as shown.

DESCRIPTION

FIG. 1 is a front, top, left, isometric view of a fire extinguisher showing my new design.

FIG. 2 is a front elevation view of the fire extinguisher of FIG. 1.

FIG. 3 is a rear elevation view of the fire extinguisher of FIG. 1.

FIG. 4 is a left side elevation view of the fire extinguisher of FIG. 1.

FIG. 5 is a right side elevation view of the fire extinguisher of FIG. 1.

FIG. 6 is a top plan view of the fire extinguisher of FIG. 1.

FIG. 7 is a bottom plan view of the fire extinguisher of FIG. 1; and,

FIG. 8 is an exploded, front, top, left, isometric view of the fire extinguisher of FIG. 1.

1 Claim, 5 Drawing Sheets(56)
